UNITED STATES PATENT OFFICE.

SOL EINSTEIN, OF CINCINNATI, OHIO, ASSIGNOR TO THE CINCINNATI MILLING
MACHINE COMPANY, OF CINCINNATI, OHIO, A CORPORATION OF OHIO.

FEED-CHANGE ARRANGEMENT.

1,120,650.

Specification of Letters Patent.

Patented Dec. 8, 1914.

Application filed June 5, 1914. Serial No. 843,218.

To all whom it may concern:

Be it known that I, Sol EINSTEIN, a citizen of the United States, and residing at Cincinnati, in the county of Hamilton and State of Ohio, have invented a new and Improved Feed-Change Arrangement, of which the following specification is a full disclosure.

This invention proposes an improved machine-tool organization and it deals with a simplification of the general arrangement of conventional machines as well as of various sub-combinations thereof.

The ultimate usefulness and efficiency of a machine-tool necessarily is very intimately related to the facility and convenience with which it may be manipulated by the attendant. One of the most important of the various hand controllers has heretofore been placed beyond the immediate reach of the attendant when stationed at the point best adapted for the observance of the progress of the work, and this awkward position was resorted to in order to reconcile certain difficulties thought otherwise to arise. That is to say, in the knee-and-column type of machine, the feed-change mechanism for determining the rate at which the table will be caused to feed during a tooling operation has in whole or in essential part heretofore been positioned on a stationary frame-unit at a point remote from the table; as for instance, closely adjacent the prime-mover or driving-pulley and on the frame-unit that supports said driving-pulley. The hand-levers for manipulating this feed-change mechanism have also been mounted immediately at said mechanism and invariably the table has intervened between such hand-levers and the station of full observation, so that the attendant has been required to leave his station of observation in order to change the rate of feed of the table. The motion has also been transmitted from this mechanism to the table by means of a series of concatenated elements, which have had to be designed to run at the varying rates determined by the feed-change mechanism, and not at a uniform speed.

Now this invention endeavors to create an organization in which the feed-change mechanism will be positioned on an appropriate frame-unit in close proximity with the bottom-face of the table or of the element providing the table-slide and preferably below

the path of travel of the table, and preferably also housed by a casing or box mounted on a frame-unit so as to project from the side thereof that extends upwardly transversely to the path of the table and facing the observation station of the attendant; and with one or more control levers mounted on that side of the box and within the immediate reach of the attendant, whereby he will be enabled to govern the rate of feed of the table without shifting his position.

Another object within the contemplation of this invention is to simplify the construction of the feed-change mechanism so that the attendant may cause the table to feed in the predetermined direction at any desired one of a multiplicity of available rates by the manipulation of a single lever or hand controller; or may either stop or reverse the direction of travel of the table by manually shifting another lever; or may cause the stopping or the reversal, or both to take place automatically by dog-action.

Another object of the preferred species of this invention is to effect a rearrangement of conventional machines whereby the entire feed-change mechanism as well as the hand-levers for operating the same will be mounted on or carried by one or more of the "floating" frame-units, *i. e.*, such as are mounted to permit of being moved bodily in a vertical direction and cause the distance to be varied between the tool-carrying member and the table, as for instance, the knee or saddle of a machine of the type illustrated.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, of which:—

Figure 1 is a side elevation of a milling machine of the knee-and-column type typifying the manner in which any given type may be reorganized to embody this invention. Fig. 2 is a diagrammatic drawing analyzing a gear arrangement such as may be used for effecting a change in the feed of the table; the various gears being brought into one plane to avoid the confusion of an ordinary drawing. Fig. 3 is a schematic drawing explaining how a single hand-controller may execute the various manipulations required for effecting twelve changes of feed, another one determining the direction of travel of the table at any one of these rates (to the right or to the left), as well as for stopping the travel at any time. Fig. 4 is a development in plan of the circumference of a cam element for giving the time and nature of the action of a shift lever or levers operating in conjunction with the single hand-controller. Fig. 5 is a development in plan of the circumference of the single hand-controller and exemplifying the schedule and nature of the means thereon contained for enabling the attendant at once to perceive the effect of his manipulation. Fig. 6 is a development in plan of a speed-change mechanism intervening between the prime-mover and the spindle. Fig. 7 is a front elevation of a machine tool, *i. e.*, an elevation as seen from the attendant's station. Fig. 8 is an enlarged side view of a means for stopping or reversing the motion, either manually or automatically. Fig. 9 is a horizontal section through line 9—9 of Fig. 8.

To obtain an adequate understanding of this invention, it should be kept in mind that the term "feed," as used herein, indicates any one of a series of relatively slow movements of the table all essentially suitable for tooling operations, and the term "feed-changer" or "feed-change mechanism" indicates only that particular device which determines the rate at which the table thus "feeds"; and it is to be distinguished from variable speed devices which affect changes not all identified with a tooling-operation, as well as from the "speed-change mechanism" herein referred to and which determines the speed of rotation of the cutter-spindle.

Before detailing the specific features of construction whereby these functions are attained it will be convenient first to describe certain major elements of a conventional milling machine. These comprise a table Y that supports the work and which is reciprocated to-and-fro to subject the work bolted thereon to the effect of the tool or cutter that is secured to an appropriate tool-supporting member here typified by a spindle X which, in this instance, is continuously rotated by power derived from

the same source or prime-mover that actuates the table. In order to enable the machine properly to execute its functions, these actuated elements must be capable of being brought into adjustable relation with one another in two directions. This is accomplished by an interponent frame-unit B that intervenes between the frame-unit A that directly supports the spindle or tool-supporting member and the frame-unit C that directly mounts the table. In the type of machine illustrated, the interponent frame-unit B is commonly termed a "knee"; the table-supporting frame-unit C is usually termed a "saddle," and the spindle mounting frame-unit A is generally termed a "column."

The chief mechanical characteristic of the interponent frame-unit B is that it provides for a relative vertical adjustment as to the spindle-mounting unit, and a horizontal adjustment as to the table-supporting unit, *i. e.*, in a direction transverse to the other.

The spindle-mounting frame-unit, or "column" A, has heretofore been that also selected to rest on the floor and thus provide a foundation for the machine, as a whole, and it has also been utilized to support or mount both the change-gear mechanism that varies the speed of the spindle, as well as the change-gear mechanism that varies the rate of feed of the table. This, however, has resulted in a very considerable inconvenience to the attendant in manipulating the machine. That is to say, the attendant must be stationed at the outer longitudinal side of the reciprocating table in order to scrutinize the action of the machine, but, when so stationed, he is out of reach of the levers that effect all the changes of the rate of feed of the table, so that, in order to make these changes he must shift his position.

This invention proposes, among other things, a rearrangement and a reconstruction of the control elements so as to free the so-called "column" of the machine from the mechanism that governs the rate at which the table shall feed, and so to locate the said mechanism, and so to combine it with other control features that the attendant, when stationed at the outer longitudinal edge of the reciprocating table (the edge remote from the frame-unit that uprises across the plane of the table), and without shifting his position, will be able, first, to change the rate at which the table feeds, *i. e.*, to vary its speed during a cutting-stroke; second, to change the direction of travel of the table, either manually or automatically; and third, to stop the movement of the table either manually or automatically. In carrying out this aspect of this invention, one of the frame-units carrying the weight of the table may assume any conventional proportions or configuration, such

as are indicated on the drawings, but with this distinction, that it is contrived also to support or carry the weight of what may be termed a "feed-change" box, *i. e.*, the casing 5 and elements constituting a change-gear mechanism such that the rate of "feed" may be varied at will. This box may also include other control features, such as the means for determining the direction of 10 movement of the table.

A more comprehensive grasp of the various aspects of this invention may perhaps be obtained by tracing the course of motion through the machine in connection 15 with a description of the structural features involved.

At a convenient point, as for example on the column A, is mounted a prime-mover P, here instanced as a pulley, and both the 20 spindle and the table may be driven by this prime-mover. Thus, the shaft p^1 , on which the pulley P is mounted, may carry a number of gears e^4 , e^3 and e^2 which (see Fig. 6) are here slidable as a unit on shaft p^1 25 (through the hand shifting means e) so that any single one of them may be meshed with the appropriate one of the gears E^4 , E^3 , E^2 , respectively, so as to impart a predetermined rate of rotation to the gears E^1 30 and E^2 . A selector carrying gears x^1 and x^2 is operated by the hand-shifting means x (see Fig. 1) so that the gear x^3 may be rotated at a series of different speeds and effect a corresponding rotation of the spindle X through the gear X^3 . Another transmission line derives motion from the prime-mover and consists of the train of gears 1, 2 35 and 3 in intermeshing relation, and the universal and extensible shaft 4 that is connected to the universal joint 5 secured to a 40 power-driven shaft 6 that is journaled in the frame-unit C between the front and rear side walls thereof, or of a box or casing C¹ forming a part of the frame-unit C. 45 Pinned to this shaft 6 is a gear 7 that meshes with a gear 8 which turns the shaft f journaled also in the front and rear side walls of the feed-change box C¹. This transmission may be regarded as an intervening or trunk line transmission, and as 50 forming a part of the entire train leading from the prime-mover to the table.

Splined to the shaft f are two shiftable units f^1 and f^2 , the one supporting gears f^3 and f^4 and the other carrying gears f^5 and f^6 . These units are shiftable for the purpose of utilizing any one of the four enumerated gears for transmitting motion to the table, and the means for accomplishing this shift will be detailed subsequently. A series of gears F¹, F², F³, F⁴, F⁵, F⁶ are journaled to rotate as a unit and are located in such relation with the aforesaid four gears that gear f^3 may be intermeshed with gear F³, or gear f^4 with gear F⁴, or gear f^5

with gear F⁵, or gear f^6 with gear F⁶, with the effect that gears F¹, F², and F³ may be caused to rotate at any one of four different speeds. Means is also provided whereby any one of these three gears (which are of different sizes) may be utilized to transmit the motion so that twelve different changes may ultimately be had. The means for doing this comprises a shaft g^5 to which is splined a shiftable member g^4 , which in the position shown by Fig. 2 operatively connects gear F³ through gear g^3 with the shaft g^5 . When shifted to the left this member g^4 likewise connects gear F¹ through gear g^1 with the shaft g^5 ; and similarly when the member g^4 is shifted to the right it connects gear F² through gear g^2 with the shaft g^5 . All rotations of the shaft g^5 are communicated to the gear g^6 and the latter permanently meshes with the gear G⁶ so as to drive the bevel G⁷. These gears constitute the transmission portions of a feed-change mechanism and they are journaled in a depending portion of the frame-unit C, which portion preferably assumes the form of a 85 box or casing C¹ which moves as a unit with the floating frame-unit C, and which in this embodiment of this invention constitutes the saddle of the machine.

The continuous rotation of the bevel G⁷ is 95 appropriately transmitted to a table propelling means capable of converting the continuous rotary motion into a reciprocating rectangular motion suitable for the actuation of the table. This may be accomplished 100 by means of a bevel 9 that meshes with bevel G⁷ and which is secured to a shaft 10 that uprises from the box C¹ and carries an upper bevel 11 which meshes with the two gears R and L journaled in the frame-unit 105 C on which the table Y slides. A shaft 13 is in loose co-axial relation with these two bevels, but may be rotated by either through the clutch member H, which is splined to the sleeve 12 that is in turn also splined to 110 the shaft 13. When the clutch H is shifted into interlocking engagement with the bevel L, the shaft 13 will be rotated to move the table to the left, and conversely the table will be moved to the right when clutch H 115 interlocks with bevel R. This mechanism constitutes a motion-reverser and it is located between the feed-change mechanism and the table. The table propelling means may merely consist of screw-threads on the 120 shaft 13 that engage with a nut 14 appropriately mounted on the table-supporting member, and one or more collars, such as 15, so that when the shaft 13 is rotated, the nut 14 will cause it to reciprocate and thus motion will be communicated to the table Y through the collars or shoulders 15. The motion-reverser comprising the clutch H may be actuated either by hand or automatically by dog action to change the direction 130

of travel of the table, or to stop the same by bringing it to the position shown in Fig. 2.

By examining the drawings it will be seen that the speed-change mechanism provides a first and second series of gears constructed so that the first series yields four different speeds proportional to the teeth of the gears f^3 , f^4 , f^5 , and f^6 and the second series yields three speeds F^1 , F^2 and F^3 . Referring to the chart shown by Fig. 5, it will be seen that when the motion flows through the gear F^1 there will be made available a series of speeds, which may be represented by the characters 1, 2, 3 and 4; but when the motion flows through gear F^2 a multiplier will be introduced into this series yielding a second series of higher values, which is represented on the chart by the characters 5, 6, 7 and 8, and in like manner when the motion flows through the gear F^3 a third series becomes available, indicated by 9, 10, 11 and 12 on the chart. The instrumentality whereby all these twelve speeds become selectively available by the manipulation of a single element will now be described.

The single hand-operated element is indicated by K and it embodies a hand-wheel 16 having the chart shown by Fig. 5 laid out on its periphery in such a way as to co-act with a pointer 17 shown best by Fig. 1. This element K is so mounted in the box C¹ that the hand wheel may be rotated to cause the pointer to travel progressively throughout the first series 1, 2, 3 and 4; and its mounting is such that it may be shifted or displaced axially to bring the pointer into registry with the second series 5, 6, 7 and 8, or with the third series 9, 10, 11 and 12. Intervening between this element K and the series of gears is an interpreting mechanism which will cause the successive gears f^3 , f^4 , f^5 , and f^6 to be brought into driving relation with gear F^1 according to the angular displacement of the element K, or similarly with the gear F^2 when the element K is displaced axially into its appropriate position. This interpreting mechanism embodies a part L which is splined axially to the element K so that it is unaffected by an axial movement of said element K, but its angular position corresponds always with the angular position of the element K, and the interpreting mechanism also embodies another part M which is conversely related to the element K, e. g., by being circumferentially splined thereto so that it is unaffected by the angular movement of the element K, although its position depends upon the exact displacement of the element K. The part L is utilized to determine how the first gear series shall be intermeshed; and the part M determines how the second or multiplier gear series is to be intermeshed or related to the first series.

65 The part L is here instanced in the form

of a sleeve, which by means of the feather 21, is splined axially to the shaft 18 of the element K thereby permitting free axial movement of the shaft 18 while being constrained to be rotated positively by said shaft. This part L provides two cam grooves L¹ and L², which are related as indicated by Fig. 4. Shifting levers 19 and 20 are operated by said cams to shift the gear-units f^2 and f^3 . Thus, when the hand-wheel 16 is turned to bring any one of the numerals 1, 5 or 9 opposite the pointer 17, the part L³ of the cam will swing the lever 19 to bring gear f^3 into mesh with gear F^3 . The other unit f^2 will be in neutral or non-meshing position by reason of the straight portion L⁰ of the cam lying axially opposite L³. Now, by turning the hand-wheel 16 to bring the pointer 17 into registry with any one of the numerals 2, 6 or 10, the portion L⁴ of cam L¹ will cause gear f^4 to mesh with gear F^4 ; the gear-unit f^2 still being in neutral position. The next turn of the hand-wheel 16 will bring the pointer 17 opposite one of the numerals 3, 7 or 11, and the gear-unit f^1 will be shifted to a neutral position by the straight portion L⁰ of cam L¹, and lever 20 will now be actuated by the cam portion L⁵ to cause gear f^5 to mesh with gear F^5 ; and in like manner the cam portion L⁶ will intermesh gear f^6 with gear F^6 . It is to be remembered that gears F^1 , F^2 , F^3 , F^4 , F^5 , and F^6 all move as a unit.

The means whereby the three different series of speeds indicated on the chart will now be described.

The shaft 18 is provided with a number of circumferential feathers or splines 22, and the part M is brought in splined relation with the element K by means of these feathers; in this instance, through the interponent part 23 which assumes the form of a spur-rod or pinion-rod, meshing on the one hand with the feathers 22 and on the other hand with teeth 24 of the part M. From this it will be seen that when the element K is shifted in an axial direction the element M will turn about its pivot 25, and its frame g will shift the gear-unit g^4 to establish a propelling or a transmitting relation from the gear F^1 through the gear g^1 when the circumferential series of manipulations 1, 2, 3 and 4 lie in registering relation with the pointer 17. By shifting the hand-wheel 16 axially to bring the pointer 17 into registering relation with the second circumferential series 5, 6, 7 and 8, another gear arrangement will be brought into effect, and thereon as will be understood from the drawings.

The means for controlling the position of the clutch-member H or so-called motion-reverser, comprises a rock-shaft N (see Fig. 9) which is journaled in the table-support and is suitably connected as by means of the offset pin 28 with the clutch-member H so

that when it lies in its intermediate position, the clutch-member will be in neutral position, and so that when it is rocked one way or the other, the clutch-member H be correspondingly shifted either to engage the bevel R or the bevel L, as the case may be, and thereby appropriately control the direction of travel of the table. This rock-shaft N is maintained in one of these three positions 10 by means of a pawl 26 which is urged by the spring 27 into seating relation with one of the three notches provided by the rock-shaft. The hand-lever O provides for a manual manipulation of the rock-shaft from 15 a station at the front longitudinal edge of the table. The motion-reverser H is also automatically controlled through the rock-shaft N by means of a dog-actuated plunger T which is also mounted near the front longitudinal edge of the table. This plunger provides a series of circumferential threads 20 that engage with teeth 30 on the rock-shaft so that the angular positions of the rock-shaft will depend upon the vertical displacement of the plunger. This displacement is determined by means of the cams 31 and 32 provided on its end. When a dog such as U rides past the plunger, its cam 33 will impact the cam 32 and depress the plunger, and when a conversely formed dog rides by it will impact the cam 32 and elevate the plunger; thereby imparting a travel of the table to the right or to the left, as the case may be. When a double-cammed dog, such as W, rides past the plunger, its contact surfaces 34 and 35 will coact with the cams 31 and 32 and bring the plunger to neutral position and stop the travel.

Having thus revealed this invention, I 40 claim as new and desire to secure the following combinations of elements, or equivalents thereof, by Letters Patent of the United States:—

1. A machine-tool organization combining a shiftable frame-unit mounted to be capable of a bodily vertical movement and providing a first slide-way and also providing a second slide-way disposed transversely to said first slide-way; a feed-change mechanism carried by said shiftable frame-unit and located at one end of said first slide-way; a table; means supporting said table and coöperating with said first slide-way to feed in the direction thereof and over said feed - change mechanism; another frame-unit coöperating with said second slide-way; a tool - supporting member; means for mounting said tool-supporting member on said other frame-unit; hand-operating means carried by said bodily-movable frame-unit for manually controlling said feed-change mechanism; and a transmission extending through said feed-change mechanism for propelling the table at the 65 rate of feed determined thereby.
2. A machine-tool of the nature disclosed combining a stationary frame-unit; a bodily-movable frame-unit; a table slidable on said bodily-movable frame-unit; a feed-screw journaled on and reciprocating with 70 said table; a feed-change mechanism carried by said movable frame-unit near one side of said stationary frame-unit and underneath said table; operating instrumentalities extending from said feed- 75 change mechanism and located at the front side of the longitudinal edge of said table; and automatic trip - means adjustably mounted at the longitudinal edge of said table and adapted to actuate said instrumentalities.
3. A machine-tool organization combining a stationary frame-unit; a tool-supporting member mounted at the upper end thereof; a table; a bodily-movable frame-unit intervening between the table and the stationary frame-unit and providing for relative movements between said frame-unit and said table in two horizontal transverse directions; a feed-change mechanism arranged below said table on said bodily-movable frame-unit and adapted to effect a relative feed between said table and said tool-supporting member in one of said directions; and a manually operable element arranged at the front of the machine-tool and constituting means for controlling said feed-change mechanism, whereby the rate of relative feed between the tool-supporting member and said table may be varied. 90
4. A machine-tool organization combining a prime-mover; a table; a frame-unit uprising across the plane of the table; a tool-supporting member located above the table and having its weight carried by said frame-unit; a feed - change mechanism; transmitting means connecting said prime-mover, said feed-change mechanism and said table; a hand-lever located adjacent the longitudinal edge of the table remote 105 from the said frame-unit; and means enabling said hand-lever to determine the operative effect of said feed-change mechanism.
5. A machine-tool organization combining a tool-supporting member; a table; a stationary frame-unit on which said member is mounted; a first bodily-movable frame-unit slidably supported by said stationary frame-unit whereby the distance between said tool-supporting member and said table may be varied; means comprising a second bodily-movable frame-unit intervening between said table and said first bodily-movable frame-unit and constructed 115 to provide for a relative movement in two transverse horizontal directions between said table and said first bodily-movable frame-unit; a feed - change mechanism mounted directly on said second-bodily 120
6. A machine-tool organization combining a tool-supporting member; a table; a stationary frame-unit on which said member is mounted; a first bodily-movable frame-unit slidably supported by said stationary frame-unit whereby the distance between said tool-supporting member and said table may be varied; means comprising a second bodily-movable frame-unit intervening between said table and said first bodily-movable frame-unit and constructed 125 to provide for a relative movement in two transverse horizontal directions between said table and said first bodily-movable frame-unit; a feed - change mechanism mounted directly on said second-bodily 130

movable frame-unit in underlying relation with the path of feed of said table; a prime-mover mounted on said stationary frame-unit; and a transmission extending 5 from said prime-mover through said feed-change mechanism to said table to propel it at a rate determined by said feed-change mechanism; and means mounted at the side of said last-mentioned frame-unit for 10 manually adjusting said feed-change mechanism.

6. A machine-tool organization combining a prime-mover; a table; a stationary frame-unit uprising across the plane of the 15 table; a tool-supporting member located above the table and having its weight carried by said frame-unit; a vertically-movable frame-unit having its weight carried by said stationary frame-unit; a feed- 20 change mechanism; transmitting means connecting said prime-mover, said feed-change mechanism and said table; a hand-lever located adjacent the longitudinal edge 25 of the table remote from the said stationary frame-unit; and means enabling said hand-lever to determine the operative effect of said feed-change mechanism.

7. A machine-tool organization combining a spindle-supporting member; a spindle 30 in journaled relation with said member; a movable table having a slide-way in its bottom-face; a movable frame-unit supporting the weight of said table; a stationary frame-unit constituting a foundation for the machine-tool and adjustably supporting the 35 weight of said movable parts; a feed-change mechanism carried by one of said movable parts; a table-propelling transmission extending through said feed-change mechanism to said table to effect a relative feed 40 of said table at a rate determined by said feed-change mechanism; and a manually-operable element mounted on said movable frame-unit and accessible from a station 45 immediately adjacent the front longitudinal edge of said table and constituting means for controlling said feed-change mechanism, whereby the rate of relative feed between the spindle and the table may be varied.

50 8. A machine-tool organization combining a prime-mover; a table; a stationary frame-unit uprising across the plane of the table; a tool-supporting member located above the table and having its weight carried by said 55 frame-unit; a mobile frame-unit carried by said stationary frame-unit; a second mobile frame-unit carried by the other mobile frame-unit; a feed-change mechanism; transmitting means connecting said prime-mover, said feed-change mechanism and said table; a hand-lever mounted on said second mobile frame-unit and located adjacent the longitudinal edge of the table remote from the said frame-unit; and means enabling

said hand-lever to determine the operative 65 effect of said feed-change mechanism.

9. A machine-tool organization combining a frame-unit providing a first horizontal slide-way and a second horizontal slide-way disposed transversely to the axis of said 70 first slide-way; a feed-change mechanism carried by said frame-unit in lateral relation with one of said slide-ways; a table overlying said frame-unit and adapted to feed in a direction transverse to said second 75 slide-way; another frame-unit co-operating with said second slide-way; a tool-supporting member; hand-operating means mounted adjacent said table for manually controlling said feed-change mechanism; and a 80 transmission extending through said feed-change mechanism for propelling the table at the rate of feed determined thereby.

10. A machine-tool of the nature disclosed combining a first frame-unit; a prime-mover 85 mounted thereon; a second frame-unit slideable with relation to said first frame-unit; a power driven transmission extending from said prime-mover and terminating at one side of said second frame-unit; a table in 90 slidable relation with said second frame-unit; a feed-screw journaled on and reciprocating with said table; a feed-change box mounted at the said side of said frame-unit underneath said table and establishing connection between said transmission and feed-screw; and hand-operating instrumentalities extending from said feed-change box and located at the front side of the longitudinal edge of said table. 100

11. A machine-tool organization combining a spindle-supporting member; a spindle in journaled relation with said member; a table; means intervening between the table and the spindle-supporting member and 105 providing for relative movement between said spindle and table in a vertical and in a horizontal direction transverse to the spindle; a casing mounted on said means at one side of the machine-tool and below 110 said table; a feed-change mechanism housed by said casing and adapted to effect a relative feed between said table and said spindle in one of said directions; and a manually operable element arranged at the front 115 longitudinal edge of said table and constituting means for controlling said feed-change mechanism, whereby the rate of relative feed between the spindle and table may be varied. 120

12. A machine-tool of the nature disclosed combining a frame-unit; a casing secured to the front side thereof; a power-driven shaft extending through the rear wall of said casing and terminating in a journal mounted on the front wall thereof; a table slidably transversely on the frame-unit; a feed-screw journaled on and reciprocating with said

table; a feed-change mechanism in said casing establishing operative connection therebetween; and hand-operating instrumentality journaled at the outer side of the front 5 wall of said casing and located forward of the longitudinal front edge of said table.

13. A machine-tool organization combining a tool-support; a frame-unit on which said tool-support is mounted; a table-support 10 slidably connected with said frame-unit to afford a relative vertical movement therebetween, whereby its distance from said tool-support may be varied; a table mounted directly on said table-support; 15 means comprising another frame-unit intervening between said table-support and said frame-unit and constructed to provide for movement in a horizontal direction between said table-support and said frame-unit; a 20 feed-change mechanism mounted directly on said table-support in underlying relation with the path of feed of said table; a prime-mover mounted on one of said frame units; and a transmission extending from said 25 prime-mover through said feed-change mechanism to said table to propel it at a rate determined by said feed-change mechanism; and means mounted adjacent said table for manually adjusting said feed- 30 change mechanism.

14. A machine-tool of the nature disclosed combining a table-support mounted to be bodily moved vertically and in a horizontal plane; a feed-change box mounted at the 35 front side thereof; an elongated table slidably mounted upon said movable table-support above said box; a feed-screw journaled on the under side of said table and reciprocating relatively to said box; mechanism 40 housed by said box for propelling said table; and hand-operated means pivoted to the front side of said box near the longitudinal front edge of said table and adapted to enable the operative capacity of said mechanism 45 to be manually determined.

15. A machine-tool organization combining a work-supporting member; a tool-supporting member; a frame; a first and a second series of gears; a hand-operated element 50 mounted on said frame and provided with position-indicating means; means operatively connecting said element with the first and the second gear-series whereby a rotation of said element will effect a shift 55 of said first gear series, and whereby another movement of said element will effect a shift of said second gear-series; and transmission means operatively connecting said speed-change mechanism in propelling relation 60 with one of said members.

16. A machine-tool organization combining a work-supporting member; a tool-supporting member; a speed-change mechanism; a casing housing said mechanism; a

single hand-operated element extending into 65 said housing and provided externally thereof with a hand-wheel having a first and a second circumferential series of indicating characters; interpreting mechanism connecting said element with said speed-change 70 mechanism, whereby a rotation of said hand-wheel will effect a progressive change throughout one series of speed-changes, and whereby, when said element is shifted in position axially, a rotation of said hand-wheel will effect progressive changes in another series of speed-changes; and transmission means operatively connecting said speed-change mechanism in propelling relation with one of said members. 80

17. A machine-tool organization combining a work-supporting member; a tool-supporting member; an element; a first part in axially splined relation with said element; a second part in circumferentially 85 splined relation with said element; and means for determining the action of one of said members and controlled by said parts.

18. A machine-tool organization combining a work-supporting member; a tool-supporting member; a first series of gears; a part adapted to be progressively moved to shift said first series of gears to enable them to yield a series of speeds; a second 95 series of gears in serial relation with said first series; a device for shifting said second series to enable the same to yield different speeds; a hand-operated element connected both with said part and with said device 100 whereby when rotated it will operate said device without operating said part, and when shifted axially it will operate said part without operating said device; and transmission means operatively connecting 105 said series of gears in serial propelling relation with one of said members.

19. A machine-tool organization combining a work-supporting member; a tool-supporting member; a frame; mechanism for 110 actuating one of said members; a hand-operated element mounted on said frame and provided with position-indicating means; means operatively connecting said element with said mechanism whereby a 115 rotation of said element will establish one operative relation between said mechanism and the element actuated thereby, and whereby another movement of said element will establish another operative relation between 120 said mechanism and one of said elements; and transmission means enabling said mechanism to propel one of said members.

20. A machine-tool organization combining a work-supporting member; a tool-supporting member; a feed-change mechanism; a casing housing said mechanism; a single hand-operated element located adjacent the

front side of one of said members and extending into said housing; means connecting said element with said feed-change mechanism whereby a rotation of said element will 5 render available a series of speed changes; a device also connected with said element to be unaffected by a rotation thereof but operated thereby when said element is shifted in position axially; and transmission 10 means operatively connecting said feed-change mechanism in propelling relation with one of said members.

21. A machine-tool organization combining a work-supporting member; a tool-supporting member; a first series of gears; a part adapted to be progressively moved to shift said gears to enable them to yield a series of speeds; a second series of gears in serial relation with said first series; a device 15 for shifting said second series to enable the same to yield different speeds, and a hand-operated element connected both with said part and with said device whereby when moved in one way it will operate said 20 device without operating said part, and when moved in another way it will operate said part without operating said device; and transmission means operatively connecting said series of gears in serial propelling relation with one of said members.

22. A machine-tool organization combining a work-supporting member; a tool-supporting member; a first series of gears; a part adapted to be progressively moved to shift said first series of gears to enable them to yield a series of speeds; a second series of gears in serial relation with said first series; a device for shifting said second series to enable the same to yield different speeds; and a hand-operated element connected both with 35 said part and with said device whereby when moved in one way it will operate said device without operating said part, and when moved in another way it will operate 40 said part without operating said device; and transmission means operatively connecting said series of gears in serial propelling relation with one of said members.

23. A machine-tool organization combining a spindle; a table; a prime-mover; a speed-change mechanism between the spindle and the prime-mover; a first transmission connecting said spindle and said prime-mover through said speed-change mechanism; a feed-change mechanism adjacent 50 the table and remote from the prime-mover; a motion-reverser between the

feed-change mechanism and said table; a second transmission adapted to connect said prime-mover, said feed-change mechanism, 60 said motion-reverser, and said table together in series in the order recited; a hand-operated member located adjacent the table; and shifting means actuated by said member for causing the table to feed at the rate determined by said feed-change mechanism and in the direction indicated by the position of said hand-operated member and determined by said motion-reverser.

24. A machine-tool organization combining a spindle; a table; a prime-mover; a speed-change mechanism between the spindle and the prime-mover; a first transmission connecting said spindle and said prime-mover through said speed-change mechanism; a feed-change mechanism adjacent the table and remote from the prime-mover; a motion-reverser between the feed-change mechanism and said table; a second transmission adapted to connect said prime-mover, said feed-change mechanism, 70 said motion-reverser, and said table together in series in the order recited; a hand-operated member located adjacent the table; and shifting means actuated by said member for causing the table to feed at the rate determined by said feed-change mechanism and in the direction indicated by the position of said hand-operated member and determined by said motion-reverser.

25. A machine-tool organization combining a work-supporting member; a tool-supporting member; a speed-change mechanism; a hand-operated element shiftable into different positions and adapted to be 75 progressively moved from each of said positions; interpreting mechanism actuated by said element for causing said speed-change mechanism to yield one series of speeds when said element is moved from one of its 80 positions and to yield another series of speeds when said element is moved from another of its positions; and transmission means operatively connecting said speed-change mechanism in propelling relation 85 with one of said members.

In witness whereof, I hereunto subscribe my name, as attested by the two subscribing witnesses.

SOL EINSTEIN.
